REEL FOR AN ELECTRICAL EXTENSION CORD

Clyde W. Smith, R.R. 4, Box 29, Bowling Green, Ohio

Filed Oct. 10, 1963, Ser. No. 76,934

Term of patent 3½ years

(Cl. D41—1)

FIG. 1 is a front quarter view in perspective showing a reel for an electrical extension cord embodying my new design;

FIG. 2 is a rear quarter view in perspective of the reel for an electrical extension cord illustrated in FIG. 1;

FIG. 3 is a front view in elevation thereof;

FIG. 4 is a rear view in elevation; and

FIG. 5 is an end view in elevation taken from the left side of FIG. 3.

The dominant features of my design reside in the portions shown in solid lines, the broken line indication of a line cord fragment within the grommet in FIGS. 1 and 2 being for illustrative purposes only.

I claim:

The ornamental design for a reel for an electrical extension cord, as shown and described.
